UNITED STATES PATENT OFFICE.

JAY H. HALL, OF CLEVELAND, OHIO, ASSIGNOR TO THE ELECTRIC CONTROLLER AND MANUFACTURING COMPANY, OF CLEVELAND, OHIO, A CORPORATION OF OHIO.

ELECTRIC CONTROLLER.

1,197,584.

Specification of Letters Patent. Patented Sept. 5, 1916.

Application filed April 25, 1911, Serial No. 623,212. Renewed July 10, 1913. Serial No. 772,416.

To all whom it may concern:

Be it known that I, JAY H. HALL, a citizen of the United States, residing at Cleveland, in the county of Cuyahoga and State 5 of Ohio, have invented new and useful Improvements in Electric Controllers, of which the following is a specification.

My invention relates to motor controlling devices, particularly that type in which magnetically operated switches are used to cut 10 out the starting resistance during the acceleration of the motor.

In controlling devices in which magnetically operated switches are used whose operating windings are energized by current in the motor circuit, it is desirable when the motor is across the line to leave in circuit only the winding of the last resistance controlling switch. This cuts down the loss 20 of power in the motor circuit due to the resistance of the switch windings and allows a more efficient design of the switches. It is also desirable to use a series connection of the resistance in the rheostat by which all of 25 the rheostat connections are connected in series with the motor when the motor circuit is first established, and then to cut the resistance out step by step until the motor is across the line. This method is preferable 30 to the multiple connection whereby the resistance sections of the rheostat are successively connected in multiple to increase the current through the motor, since for nearly 35 all sizes of motors the series system of connection is more efficient.

The object of my invention is to provide a motor controller by which the rheostat sections are connected in series to start the motor, and that when the last resistance 40 controlling switch closes it will cut out of circuit all of the starting resistance and also the windings of the other resistance controlling switches.

To further describe my invention I will 45 refer to the accompanying drawing, which shows a wiring diagram of a controlling device embodying my invention. In this drawing I show a knife switch S for connecting the motor and controller to a source of supply. The armature of the motor is represented by A, the shunt field by f, the starting

resistance or rheostat sections by R' , R^2 , R^3 , and the resistance controlling switches S' , S^2 , S^3 , having operating windings C' , C^2 , C^3 , respectively. 55

The type of resistance controlling switches shown is the type described in Eastwood's Patent, No. 1,040,292, granted October 8, 1912, which has the peculiarity of being locked open when the current through the 60 winding is above a predetermined value. Upon the lowering of the current in the winding of the switch to this value, the switch will operate and close its contacts.

It will be seen from the drawing that each 65 switch in closing short-circuits a section of the rheostat, and at the same time energizes the winding of the next succeeding switch, which insures that the switches will close in a predetermined order. Furthermore, the 70 switches remain closed as long as any current flows through their windings, and therefore do not open their contacts when any appreciable amount of current is flowing 75 therein. The switch contacts therefore do not require any magnetic blow-out devices to protect them from serious arcing.

The operation of the controller is as follows: Upon closure of the knife switch S the shunt field f is immediately excited. A 80 circuit is also established through the motor armature A, the starting resistance R^2 , R' , the winding C' of the switch S' , and the starting resistance R^3 to the negative side of the switch S. This starts the motor with 85 all of the rheostatic resistance in series with the armature, the amount of current flowing depending upon the value of the resistance. This value of current will be sufficient to lock open the switch S' and it will remain 90 open until the motor has speeded up and caused the armature current to diminish to the value at which the switch S' is adjusted to operate. At this point the switch S' will 95 close its contacts, short-circuiting the resistance section R' and energizing the winding C^2 of the switch S^2 . The increase of current in the motor circuit due to the short-circuiting of the resistance R' is sufficient to lock open the switch S^2 , and this switch remains open until the motor has further increased its speed and caused the armature

current to diminish to the point at which the switch S^2 will operate, at which time it will close its contacts, whereby the resistance section R^2 is short-circuited and the winding 5 C^3 of the switch S^3 is energized. The increased value of the armature current caused by the short-circuiting of the resistance section R^2 will lock open the switch S^3 . It will be noticed that the motor current now flows 10 from the positive line through the armature A, the switch winding C' , the contacts of the switch S^2 , the switch winding C^2 , the contacts of the switch S' , the winding C' , and the resistance section R^3 to the negative 15 line. When the armature current has again diminished owing to the speeding up of the motor to the point at which the switch S^3 will operate, this switch will close and short-circuit the resistance section R^3 by a path 20 which does not include the windings C^2 and C' . These windings are immediately deenergized and the switches S' and S^2 drop open. The motor is now connected across the line, having in its circuit only the winding 25 C^3 of the switch S^3 , which holds this switch closed so long as any current flows in the armature circuit or until the motor is stopped by the opening of the switch S . It will be understood that the knife switch 30 S can be replaced by any arrangement of main switches including one or more magnetically operated switches, or by a reverser for the motor. It will be also understood that my invention can be applied to other 35 forms of motors, such as series or compound-wound, and that it may be applied to translating devices other than motors.

I claim—

1. In a motor controller, a motor, a series of resistance sections, means connecting the motor to a source of supply in series with said sections to start the motor, a series of normally open switches for cutting out the resistance sections successively, 40 an operating winding for closing each switch of the series energized by current through the motor, and a shunt including contacts closed by the last switch and short-circuiting the windings of the other 45 switches in the said series, whereby the said other switches are caused to open.

2. In a motor controller, a circuit for the motor, resistance sections for said circuit, magnetically-operated switches for shunting said sections successively, the operating windings of said switches being connected in the said circuit, means first connecting said circuit to a source of supply including said sections and one of said windings, and 50 a shunt controlled by the last switch and short-circuiting the last section of the said resistance and the said windings of the other switches, whereby the said other switches are caused to open.

65 3. In a circuit to be controlled, a plural-

ity of resistance sections, a plurality of switches having windings in the said circuit and adapted to cut out the said sections successively, and means controlled by the last switch to close for short-circuiting the 70 last resistance section and the said windings of the other switches, leaving the winding of the last switch still in said circuit and causing the said other switches to open.

4. In a motor controller, a motor, a circuit therefor, resistance sections for the said circuit, a series of switches adapted to close in a predetermined order for controlling the said resistance sections, windings for the switches energized by current through the 75 motor, means first connecting the said sections all in series in the motor circuit, and means for cutting out the windings of the other switches when the last switch of the series closes, whereby the said other switches 80 are caused to open.

5. In a circuit to be controlled, a series of resistance sections, a series of switches for controlling said sections, arranged to close in a predetermined order, windings for the 85 switches connected in the said circuit, means first connecting in series in the circuit the said resistance sections and the winding of the first switch of the series, and means for cutting out the windings of all the switches 90 in the series except the last and causing all the switches except the last to open.

6. In an electric controller, a motor, a series of resistance sections, a series of switches for controlling said sections, windings for the 95 switches energized by the motor current, means connecting the motor to a source of supply in series with said sections and the winding of the first switch of the series, means controlled by each switch in closing 100 to cut out a section of said resistance and energize the winding of the next succeeding switch, and means for cutting out the windings of all the switches in the series except 105 the last and causing all the switches except 110 the last to open.

7. In a motor controller, a motor, a series of resistance sections, means connecting the motor to a source of supply in series with said sections to start the motor, a series of 115 normally open switches for cutting out the resistance sections successively, a winding energized by current through the motor for delaying the closure of each switch and for holding it closed, and a shunt including 120 contacts closed by the last switch and short-circuiting the windings of the other switches in the said series whereby the said other switches are caused to open.

8. In a motor controller, a circuit for the 125 motor, resistance sections for said circuit, electromagnetic switches for shunting said sections successively, the energizing windings of said switches being connected in the said circuit, means first connecting said cir- 130

cuit to a source of supply including said sections and one of said windings, and a shunt controlled by the last switch and short-circuiting the last section of the said 5 resistance and the said windings of the other switches whereby the said other switches are caused to open.

Signed at Cleveland, Ohio, this 22nd day of April, A. D. 1911.
